UNITED STATES PATENT OFFICE

2,508,557

ECCENTRIC FOLLOWER MECHANISM

George B. Wood, Jr., Springfield, Mass., assignor
to American Bosch Corporation, Springfield,
Mass., a corporation of New York

Application November 15, 1946, Serial No. 710,001

8 Claims. (Cl. 74—569)

1

This invention relates to a new and improved eccentric follower mechanism and more particularly to a relatively compact, lightweight, rugged eccentric follower mechanism which will stand greater load than roller mechanism of comparable bulk, weight and inertia of the moving parts. An object of the invention is to make a relatively compact, lightweight, rugged eccentric follower mechanism wherein the parts are retained in assembled relation for handling.

Another object of the invention is to provide a new and improved follower mechanism of the type set forth wherein the center about which the shoe pivots is retained close to the face of the shoe.

Another object of the invention is to provide an eccentric follower mechanism of the type set forth which employs a relatively small rocker pin and wherein the bearing is obtained along the full length of the top and bottom of the rocker pin thereby providing a maximum bearing area with a relatively small pin.

Other objects and advantages of the invention will be apparent from the following description taken in connection with the accompanying drawings. It will be understood that many changes may be made in the details of construction and arrangement of parts without departing from the scope of the invention as expressed in the accompanying claims, the preferred form of the invention having been given by way of illustration only.

Referring to the drawings:

Fig. 1 is a side view, partially in section, of a follower mechanism embodying the invention;

Fig. 2 is a fragmentary end view of the device shown in Fig. 1;

Fig. 3 is a sectional view taken on line 3—3 of Fig. 2 looking in the direction of the arrows;

Fig. 4 is an exploded view of the follower mechanism but showing the side thereof similar to Fig. 1; and

Fig. 5 is an exploded view of the parts shown in Fig. 4.

Referring more particularly to the drawings, wherein similar reference characters designate corresponding parts throughout the several views, the arrangement shown embodying the invention comprises the eccentric or cam 1 on the shaft 2 and adapted to be rotated or oscillated by the movement of said shaft 2.

The eccentric follower mechanism embodying the present invention comprises the shoe 3, rocker pin 4 and tappet 5.

The shoe 3 has the follower surface 6 adapted

2

to engage the surface of the eccentric 1 and where the apparatus is to be used with a rotating eccentric or cam 1, the relief 7 may be provided.

The shoe 3 has, at its opposite ends, projections 5 or ears 8 and the bore 9 in which the rocker pin 4 is adapted to be positioned. The bore 9 through the projections 8 is of such size that the projections 8 envelop the rocker pin 4 and the tappet 5 has the central portions 10 having the bore 11 also adapted to envelop the rocker pin 4, so that when the shoe 3 and tappet 5 are in assembled relation and the pin 4 slid into operative position through the aligned bores 9 and 11, the parts will be retained in operative relation.

15 Except for the central area or portions 10 of the tappet 5 and the edge portions or areas 8 of the shoe, the adjacent surfaces or portions of the tappet and shoe may be formed of desired contour or shape so long as they allow envelopment 20 of the pin 4 as described above and do not touch and thereby allow clearance for free action or movement of the shoe 3 upon movement of the eccentric 1.

The collar 12 prevents the rocker pin 4 from 25 sliding out of the aligned bores 9 and 11 and is retained in position by the coil spring 13 which engages the lower surface of said collar 12 and at its other end engages the wall of the annular 30 opening 14 in the guide 15 which has a central bore adapted to receive an extension 16 on the tappet 5. The housing 17 and holding pin 18 are provided for retaining the parts in position as shown in Fig. 1.

As shown in detail in Fig. 3, the surface 19 of 35 the shoe 3 could be a plane surface and the adjacent surface 20 of the tappet 5 could be a conical or curved surface to allow free action of the shoe 3 relative to the tappet 5 as described above.

From the above it will be seen that with the 40 present construction a relatively compact, lightweight, rugged eccentric follower mechanism may be constructed which will stand greater load than a roller mechanism of comparable bulk, weight and inertia of the moving parts, and that in the 45 present construction a maximum bearing area along the full length of the top and bottom of the rocker pin 4 will be obtained, thus providing maximum bearing area with a relatively small rocker pin and that by forming portions of the shoe 3 and tappet 5 to envelop the rocker pin 4, that the parts will be retained in assembled relation for handling.

From the foregoing it will be seen that I have 50 provided simple, efficient and economical means

for obtaining all of the objects and advantages of the invention.

Having described my invention, I claim:

1. An eccentric follower mechanism having a shoe and a tappet which are joined by a pin which is sufficiently enveloped by both said shoe and said tappet to retain the parts in assembled relation and which pin has substantially full length contact in said shoe and said tappet.
2. An eccentric follower mechanism comprising a pin, a shoe having a portion adapted to engage a cam, a tappet having a portion adjacent said shoe and said pin having portions thereof sufficiently enveloped by said shoe and said tappet to retain the parts in assembled relation.
3. An eccentric follower mechanism comprising a pin, a shoe having a portion adapted to engage a cam, a tappet having a portion adjacent said shoe and said pin having portions thereof sufficiently enveloped by said shoe and said tappet to retain the shoe and tappet in assembled relation, said pin having substantially full length bearing in said shoe and said tappet.
4. An eccentric follower mechanism comprising a pin, a shoe having a portion adapted to engage a cam, a tappet having a portion adjacent said shoe and said pin having portions thereof partially enveloped by said shoe and said tappet, said pin having substantially full length bearing along one side thereof with said shoe and along its opposite side with said tappet.
5. An eccentric follower mechanism comprising a shoe and a tappet, and a rocker pin engaging said shoe and tappet to retain the same in assembled relation, said rocker pin being sufficiently enveloped by said shoe and said tappet to retain the parts in assembled relation and said pin having substantially full length bearing in said shoe and in said tappet.
6. An eccentric follower mechanism comprising a shoe and a tappet, a pin member for retaining said parts in assembled relation, said shoe and

said tappet having portions partially enveloping said pin, and having portions of such contour as to allow free, relative movement of said shoe and tappet, said pin having substantially full length bearing in both said shoe and said tappet.

7. An eccentric follower mechanism comprising a pin, a shoe having a portion adapted to engage a cam, a tappet having a portion adjacent said shoe, said pin having portions thereof sufficiently enveloped by said shoe and said tappet to retain the parts in assembled relation, said pin having substantially full length bearing in both said shoe and said tappet and means adjacent the opposite ends of said pin for retaining said pin in said assembled position.

8. An eccentric follower mechanism comprising a pin, a shoe having a portion adapted to engage a cam, a tappet having a portion adjacent said shoe, said pin having portions thereof sufficiently enveloped by said shoe and said tappet to retain the parts in assembled relation, said pin having substantially full length bearing in both said shoe and said tappet and a ring having portions adjacent the opposite ends of said pin for retaining said pin in said assembled position.

GEORGE B. WOOD, JR.
